UNITED STATES PATENT OFFICE.

EUGENE W. VOGEL, OF CHICAGO, ILLINOIS.

DESIGN FOR A CASING FOR RAILROAD SIGNAL MECHANISM.

SPECIFICATION forming part of Design No. 35,268, dated November 5, 1901.

Application filed September 16, 1901. Serial No. 75,621. Term of patent 7 years.

To all whom it may concern:

Be it known that I, EUGENE W. VOGEL, a citizen of the United States, and a resident of Chicago, Cook county, State of Illinois, have invented and produced a new and useful Design for a Casing for Railroad Signal Mechanism; and I do hereby declare that the following is a specification thereof, reference being had to the accompanying drawing and to the reference characters marked thereon, and in which the figure is a perspective view of a casing for railroad signal mechanism embodying my design.

The casing A comprises an upper inclosed part A' and a lower reticulated portion A². The upper inclosed portion A' is rectangular in shape and comprises front, side, and top walls adapted to surround the operating mechanism of the bell and protect the same from the weather and also from injury at the hands of unauthorized persons. The lower portion A², in which is adapted to be incased the gong and clapper of the bell, is circular in form and is provided with interstices.

The two parts of the casing are united by a connecting-rod a³, which extends through registering perforations in lugs a' and a², projecting, respectively, from the upper and lower parts of the casing.

The lower part A² of the casing is provided with perforated ears a, by which it may be secured to a support, while the upper part A' has a projecting perforated lug a⁴ for securing the same to a support.

Having described my design, what I claim as new, and desire to secure by Letters Patent, is—

The design for a casing for railroad signal mechanism, substantially as shown and described.

In witness whereof I have hereunto subscribed my name in the presence of two subscribing witnesses.

EUGENE W. VOGEL.

In presence of—

GEO. L. WILKINSON,
CLARA C. CUNNINGHAM.
